175,149

NARROW WOVEN FABRIC OR SIMILAR ARTICLE

Leo Beer, Hartsdale, N. Y.

Application July 26, 1954, Serial No. 31,595

Term of patent 7 years

(Cl. D92—1)

The figure is a plan view of a piece of narrow woven fabric showing my new design.

A design unit is shown between the dot dash lines and is repeated as indicated.

I claim:

The ornamental design for a narrow woven fabric or similar article, as shown and described.
